HOLE CUTTER FOR SHEET MATERIAL

John M. Abrams, Brooklyn, N. Y.

Application March 21, 1944; Serial No. 527,567

12 Claims.

(Cl. 30—19)

The invention relates to a hole cutter such as may be utilized, for example, in opening the tops of sealed containers, and adapted for manual operation to cut a disk section out of such tops or other thin material.

Another object of the invention is to provide a hole cutter of simple construction which will lend itself to ready and relatively inexpensive manufacture.

Still another object of the invention is to provide such an assembly of a supporting and manipulating frame element and a cutter element that the respective elements may be rearranged, as for transportation purposes, in a manner to prevent contact with the cutting and other sharp portions of the cutter device until it is desired to make use of such device.

In carrying out the invention, a circular flanged frame or cupped disk is provided with means such as a pair of diametrically disposed radial lugs for rotating the cutter manually to cut the desired opening, said frame frictionally retaining a cutter-bearing element having a central offset portion which is designed to engage the inner end of a portion of the frame projecting axially inwardly, for example, as an open-ended tube. There is preferably mounted over said frame and the tubular portion a detachable closure element or cap upon which pressure may be exerted in setting the frame in position for the cutting operation.

For effecting such location of the frame, there is supported by the cutter-bearing element one or more prongs which extend outwardly from the offset engaging portion of said cutter-bearing element, whereby the pressure exerted on the closure element will be transmitted, through the tubular portion and the offset portion engaging therewith, to the prongs carried by said engaging portion which puncture the material. This will serve to position firmly the cutter for rotation about the prongs which are rotatably connected to the cutter element at its said offset engaging portion; and upon completion of the cutting operation the disk cut out thereby is prevented from falling into the interior, for example, of a container, through the provision of barbs at the outer ends of the respective prongs located below the cutting plane and upon which the severed disk will rest. The disk will then be withdrawn with the cutter device by pulling up on the latter, whereupon if it be desired to then again close the opening thus provided, this may be accomplished by detaching the cover or cap element from the frame and placing the same in inverted position in the opening, said cap having a raised rim portion of greater diameter than the opening.

A further advantage of the novel construction of cutter is that the assembly of the elements may be rearranged, as for transportation purposes, to completely enclose the cutting elements and

prongs merely by reversing the cutter-bearing element and forcing it into the lower portion of the frame with the prongs accommodated within the tubular portion thereof.

The nature of the invention, however, will best be understood when described in connection with the accompanying drawing, in which:

Fig. 1 is a plan view of the novel hole cutter.

Fig. 2 is a side elevation thereof, and Fig. 3 a front elevation.

Fig. 4 is a vertical section through the cutter taken on the line 4—4, Fig. 1, with a cut-out disk indicated in broken lines.

Fig. 5 is a similar section taken on the line 5—5, Fig. 1.

Fig. 6 is a detached view of the cutter element of the novel cutter.

Fig. 7 is a fragmentary view, partly in section, of a modified form of a cutting member; and Fig. 8 is a similar view of one of the prong members carried by the cutter element.

Fig. 9 is a fragmentary view, partly in section, of a modification in the arrangement of the prong members.

Fig. 10 is a fragmentary view, partly in section, of a container with opening sealed by one of the elements of the novel hole cutter.

Fig. 11 is a view in elevation illustrating the assembly of the elements for transportation purposes.

Referring now to the drawing, a frame element of metal or other substantial material is provided, the same being in the nature of a cupped disk 20 having the flange or rim portion 21 and a central inwardly-turned and, preferably, tubular portion 22 affording a well or recess 23 of the frame element. There is provided on said frame one or more radial lugs such as the radially outwardly extending pair of diametrically disposed lugs 24 for manually rotating the hole cutter in cutting a hole therewith, for example, in the top of a container, or through other thin material. These lugs may conveniently be provided by turning out a portion of the flange 21 along its outer edge.

Over this frame element is designed to fit a suitable closure element such as the cap 25 which is frictionally retained thereon for ready removal when said cap is to be utilized as a closure for an opening cut by the novel hole cutter. To this end, the outside diameter of the cap is made to conform to the diameter of the hole made by the hole cutter, and a raised rim portion 26 is provided for said cap of greater diameter than the opening to prevent the closure member from dropping therethrough.

Within the frame 20 is designed to be retained frictionally, so as to be readily removable for the purpose hereinafter set forth, a cutter-bearing element 30. This element is in the nature of a bar provided with an off-set or engaging

central portion 31 designed to contact or engage with the inner end of the inturned tubular portion 22. The bar has its opposite ends doubled upon themselves to provide pairs of bearing arms 32 and 33, respectively, for retaining suitable cutter members. These are preferably of the rotary disk type or cutting wheels 34 and 35, respectively, mounted on corresponding spindles retained by the respective bearing arms; or, they may be of the fixed, well-known triangular or blade type 36, Fig. 7 of the drawing. In either case, the cutting plane of the cutter members is below the lowermost edge of frame element 20 and below the cutter-bearing element 30. Pairs of spaced lugs 21 turned inwardly from the rim 20 engage the opposite ends of the bar 30, when mounted in the frame, to prevent relative rotation between said frame and the cutter-bearing element when operating the cutter device manually.

In addition, the cutter-bearing element carries one or more prongs, such as the prongs 40, which are rotatably carried by said element from its offset engaging portion 31. The prongs may conveniently be provided as a unitary U-shape member loosely riveted to the portion 31 to be coaxial with the tubular portion 22 when the elements are assembled, as indicated.

Each of the said prongs, furthermore, is provided with a barb 41, the prongs extending sufficiently below the cutting plane so that these barbs will also lie slightly below the same in order to retain a cut-out portion such as the disk 42, indicated in broken lines, Figs. 4 and 5. As indicated in Fig. 9, an additional prong 43 may be provided by extending, for example, the rivet 44 between the prongs 40 and somewhat beyond their outer ends; and an enlargement 45 is provided on the rivet to shoulder against the under face of portion 31. This additional prong will facilitate positioning the cutter device preparatory to a cutting operation, and a single barbed prong 40 only may be required, as shown.

In operating the novel hole cutter, for example to cut a hole 46 in the top of a container 47, the assembled elements, as indicated in Figs. 1-3, are merely placed over the top and pressure is exerted upon the closure element or cap 25, for example by pressing thereon with the palm of the hand. This may readily be done as the outer surface of the cap is perfectly smooth and the pressure thus exerted may be transmitted through the walls of tubular portion 22 directly to the offset engaging portion 31 to force the prongs 40 through the material of the top. The cutter device is thereby anchored, and by then rotating it as a whole through digital pressure on the lugs 24, a disk 42 will be cut from the top by the cutter members 34 and 35, leaving the hole 46.

In withdrawing the cutter device, disk 42 will follow as it has in the meantime been caught by the barbs 41 of the prongs 40 and has not fallen into the interior of the container. If it be desired to again close the container, for example temporarily, at the said opening 46, cap element 25 may serve an additional purpose by detaching it from the assembly and inserting it in inverted position into the said opening 46, as indicated in Fig. 10.

An additional feature of the novel assembly resides in the ready removability of the cutter-bearing element from the assembly, allowing of its

return in reversed position into the frame, Fig. 11, with the prongs accommodated in the well 23 of the tubular portion of said frame and the cutter members protected by the doubled end portions forming the bearing arms for said cutter members. This affords a more satisfactory arrangement as for shipping or storage purposes, the cutting portions of the assembly being suitably protected and incapable, also, of causing personal injury in handling the temporarily rearranged elements.

I claim:

1. A hole cutter, comprising a circular flanged frame having circumferential means for rotating the cutter manually and a central inturned portion, and a cutter-bearing element with separated cutters, said element being held within the frame and having a central portion to engage the inner end of said inturned portion of the frame, together with prongs secured to the central engaging portion and extending outwardly beyond the cutting plane of the cutters.
2. The hole cutter of claim 1, wherein the cutter-bearing element is frictionally retained within the frame.
3. The hole cutter of claim 1, wherein the cutter-bearing element is frictionally retained within the frame, and means are provided to hold the cutter-bearing element against rotation relatively to the frame.
4. The hole cutter of claim 1, wherein the means for rotating the cutter are radial lugs diametrically disposed on the frame.
5. The hole cutter of claim 1, wherein the cutter-bearing element is frictionally retained within the frame and comprises a bar with ends doubled upon themselves to provide arms for supporting respective cutter members.
6. The hole cutter of claim 1, wherein the cutter-bearing element is frictionally retained within the frame and comprises a bar with ends doubled upon themselves to provide arms for supporting respective cutter members, and lugs are turned inwardly from the flange of the frame for engaging the opposite ends of said bar to prevent its rotation relative to said frame.
7. The hole cutter of claim 1, wherein the frame is a cupped disk from the wall of which the lugs extend radially outwardly, and a tubular portion is directed centrally inwardly from the cupped disk.
8. The hole cutter of claim 1, wherein the cutter-bearing element is detachable from the frame for fitting in reverse position therein.
9. The hole cutter of claim 1, wherein the cutter-bearing element with prongs is detachable from the frame and adapted to fit therein in reverse position with said prongs extending into a tubular inwardly-directed portion of the frame.
10. The hole cutter of claim 1, wherein the prongs of the cutter-bearing element are rotatably secured to its central engaging portion.
11. The hole cutter of claim 1, wherein the prongs are barbed, the barbs thereof being located below the cutting plane of the cutters.
12. The hole cutter of claim 1, wherein the prongs of the cutter-bearing element are rotatably secured to its central engaging portion by means of a rivet which is extended between said prongs and beyond the same, being pointed at its outer end.

JOHN M. ABRAMS.
